UNITED STATES PATENT OFFICE.

LEWIS GINTER YOUNG, OF NEW YORK, N. Y.

FLYING-MACHINE.

1,109,892.

Specification of Letters Patent.

Patented Sept. 8, 1914.

Application filed June 10, 1912. Serial No. 702,867.

To all whom it may concern:

Be it known that I, LEWIS GINTER YOUNG, a citizen of the United States, and resident of New York city, New York, have invented 5 certain new and useful Improvements in Flying-Machines, of which the following is a specification containing a full, clear, and exact description, reference being had to the accompanying drawings, forming a part 10 hereof.

My invention relates to improvements in flying machines, the principal object of which is to construct a flying machine wherein the center of the sum of the supports of the machine is fixed relative to the center of the sum of the weights (or center of gravity), regardless of any adjustment of the machine or its inclination to the horizontal.

Another object is the construction of the supporting or sustaining planes, wherein the angle of ascendance is prolonged to the extreme end in a semi-circle, so that should the machine dip at an angle to the line of 20 flight, the ends of the supporting planes oppose the same resistance to the incoming air, and produce the same action as the front cutting edge of the supporting planes.

Another object is to have the ends of the 25 supporting planes or wings independently flexible or adjustable, and also flexible or adjustable independently of the adjustment of the supporting planes, so that practically the same results may be obtained by the independent flexing or adjusting of the ends 35 only as is obtained by the warping of the entire supporting or sustaining planes.

Another object is to construct a machine 40 having a flexible body and tail portion, which can be gradually curved upwardly or downwardly, so that the chord of its curvature is the prolongation of the chord of the main supporting plane, and to mount the flexible body portion in a rigid framework 45 removed from the flexible body portion, so that the wiring from said rigid framework is led to the flexible body and tail portion at the proper angle for the easy flexing or adjustment of the flexible body and tail portion.

Another object is to have the supporting 50 planes so arranged that the angular relation thereof to the horizontal may be varied by the relative movement of the framework in 55 which the planes are mounted to the body of the machine, and to provide for the support-

ing planes for their protection a skid or shock absorber mounted beneath the planes, and also the employment of drags beneath the planes.

This application is an improvement on the application filed by me June 14, 1911, Serial No. 633,041, especially in the construction of the supporting planes, the mechanism for adjusting and supporting the same, the specific construction of the flexible body and tail portion, and the framework for the flexible body portion.

With the above purposes in view, my invention consists in certain novel features of 70 construction and arrangement of parts which will be hereinafter more fully described, pointed out in the claims, and illustrated in the accompanying drawings, in which:

Figure 1 is a longitudinal central section of the machine, in a position ready to ascend; Fig. 2 is a front elevation; Fig. 3 is a top plan view, having a part of one of the supporting planes broken away; Fig. 4 is 80 an enlarged sectional view of the front rigid body portion of the machine; Fig. 5 is a front sectional elevation taken on the line 5—5 of Fig. 4; Fig. 6 is a front elevation of the terminal portion of one of the supporting planes, disclosing the drag underneath the plane and the yielding skid for the plane; Fig. 7 is a detailed sectional view of the lower end of a tube carried by the transverse framework in which the planes are 85 mounted; Fig. 8 is a top plan view of the tip or terminal portion of one of the supporting or sustaining planes; Fig. 9 is an end view of the terminal portion of one of the supporting or sustaining planes; Fig. 10 is a 95 section taken on the line 10—10 of Fig. 8; Fig. 11 is a rear view of the terminal portion of one of the supporting planes looking in the direction of the arrow a of Fig. 10; Fig. 12 is a horizontal section taken on the 100 line 12—12 of Fig. 4; Fig. 13 is a transverse section taken on the line 13—13 of Fig. 4; Fig. 14 is a detailed side elevation of a lever and ratchet wheel employed in the mechanism which flexes, bends or adjusts the rear 105 flexible body portion of the machine and operates or changes the angle of the supporting planes; Fig. 15 is a detailed side elevation of the upper end of the levers which operate the frame and the rear flexible body 110 and tail portion of the machine, illustrating the means for locking the levers together;

Fig. 16 is a detailed section taken on the line 16—16 of Fig. 15; Fig. 17 is a detailed perspective illustrating the construction by means of which the supporting planes are pivoted to the triangular framework; Fig. 18 is a diagrammatic perspective of a part of the rear flexible body and tail portion of the machine, the wiring connected thereto for flexing, bending or adjusting the same, 5 pulleys for drawing the wiring and the operating levers, and connections for operating the triangular framework; Fig. 19 is a side elevation of the differential pulleys for operating the wiring, having the wiring applied thereto; and Fig. 20 is a top plan view of the differential pulleys which operate the wiring for flexing, adjusting or bending the rear flexible body and tail portion of the machine.

20 Referring by numerals to the accompanying drawings: 1 indicates a casing of any suitable material which forms part of and incloses the front rigid body portion of the machine, which rigid body portion is constructed in any suitable mechanical manner, and generally according to the construction shown, comprising longitudinally extending metallic channels 2, suitably connected by means of members 3, all of said 25 parts being secured to hoops or bands 4.

5 indicates a motor of any suitable type or construction, and 6 a propeller of any suitable type or construction.

7 indicates the fuel tank and 8 the aviator's seat. The motor, fuel tank and aviator's seat are inclosed in the casing 1, a suitable opening 9 being formed for the entrance and exit of the aviator to and from the machine.

40 10 indicates the main supporting or sustaining planes, which are identical in construction and method of operation, and are pivoted at their inner ends to the rigid body portion of the machine by means of pivot 45 pins 11. The main supporting or sustaining planes 10 have a fixed angle of incidence and are set on the machine at a dihedral angle, and this angle may be varied by moving them upwardly or downwardly. The 50 framework of the supporting planes is constructed of longitudinal and transverse spars or ribs, and is covered with silk or any suitable fabric or material for wing or supporting plane construction. The tips or 55 outward terminal portions of the supporting or sustaining planes 10 are constructed as shown in Figs. 2, 3, 6, 8, 10 and 11, from which it will be seen that the angle of ascendance is prolonged to the extreme end 60 in a semi-circle, so that should the machine dip at an angle to the line of flight, the ends of the supporting planes oppose the same resistance to the in-coming air and produce the same action as the front cutting edge of 65 the supporting planes. It will be further

observed that the bottom surface is concaved, as at 12, and that the rear tips or terminal portions of the supporting planes are preferably flexible, and are capable of being flexed, bent or adjusted.

13 indicates a flexible rod or member carried by or secured to the supporting planes or wings, the free end of which is mounted in a guide-way 14 of a bracket 15 carried by the planes. The free end of this rod 13 is 70 capable of being moved up and down in this guide-way, as illustrated in Figs. 10 and 11, wherein the lower or normal and upper or maximum adjustment of this rod is shown. By moving this rod upwardly and downwardly in the manner hereinafter described, the rear terminal portion of the plane and part of the end may be flexed, bent or adjusted, which obviates the necessity of flexing, adjusting or bending the entire supporting plane. When this rod is moved upwardly to its maximum adjustment, as shown in dotted lines in Figs. 10 and 11, the effective supporting force or power of the planes is lessened and the resistance is lessened. When the flexible member is down to its normal position, also illustrated in Figs. 10 and 11, the plane has its maximum effective supporting force or power and resistance. Should the machine tend to dip at an angle to the direction of line of flight, by the peculiar formation of the terminal portion of the planes, that is, by being concaved, as at 12, they will offer practically the same resistance as the front cutting edge.

100 The flexing, adjusting or bending of the terminal portion of the supporting or sustaining planes is accomplished as follows: One end of a wire 16 is secured to the flexible member 13 and a wire 17 is likewise secured to the rod or member 13, and these wires 16 and 17 are fed through the tube 18 which is mounted in the planes, and through the tubular transversely disposed framework in which the planes are mounted, and are attached to foot levers 19 (see Fig. 4). There are two such foot levers for the entire machine, one for each plane. These foot levers are mounted on a shaft 20. When the wire 17 is drawn by means of its connected foot lever, the flexible member 13 will be elevated, as illustrated in Figs. 10 and 11, and assuming that the flexible member 13 is at its upper adjustment, as shown by dotted lines in Figs. 10 and 11, by pulling the wire 16 by operating its connected foot lever, the flexible member 13 is pulled downwardly. Secured to the upper end of the tube 18 and to the upper end of the bracket 15 is a stay wire 21, and secured to the lower end of the bracket 15 and to the lower end of the tube 18 is a stay wire 22.

110 23 indicates a stay wire which is secured to the terminal portion of the supporting or sustaining planes, and is passed through 115

- the tube 18 at its lower end over the pulley 24 and then passed through and over the pulley 25 mounted in the supporting plane, and then through the upper end of the tube 18 over a similar pulley and then secured to the terminal portion of the plane. This stay wire, as stated, is mounted on pulleys so that it may move or give and not interfere with the adjustment of the planes.
- 10 The supporting or sustaining planes 10 on each side of the machine are mounted in a triangular, tubular framework. This triangular transversely disposed tubular framework is constructed of tubing and extends an equal distance on each side of the rigid body of the machine, and is constructed of transversely disposed tubes 26 extending above and across the rigid body portion of the machine and transversely disposed tubes 27 passed across and beneath the machine. The tubes 26 are connected together throughout their lengths by horizontal tubes 28, and the tubes 26 and 27 are connected together by means of vertical tubes 29, which vertical tubes 29 pass through elongated openings 30 in the supporting planes. Midway of the tubes 26 and 27 said tubes are connected together by means of four somewhat heavier tubes 31, which pass through the casing 1 and through the rigid body portion of the machine, and are mounted in brackets 32 secured to the framework of the machine. These tubes 31 constitute and form part of the triangular framework; and consequently the triangular framework itself is capable of movement relative to the body of the machine.
- When the machine is resting on the ground, the machine body is arrested by means of collars or shoulders 33 secured to the tubes 31. The upward movement of the body portion of the machine or the downward movement of the triangular framework, as the case may be, is arrested by means of collars or shoulders 34. In other words, the relative movement of the triangular framework to the rigid body portion is limited by the collars 33 and 34 secured to the tubes 31. If we assume that the triangular framework is held fixed, if the body is moved upwardly on the tubes 31, the supporting planes 10 would be moved; that is to say, they will be caused to assume more of a horizontal position, and by lowering the body in such an instance, the outward terminal portions of the planes would be elevated. In other words, the relative movement of the framework to the body of the machine varies the dihedral angle of the supporting planes, or their angular relation to the horizontal. Each supporting plane 10, aside from being pivoted at its inner end to the rigid body portion of the machine, is also pivoted intermediate of its ends to the triangular framework heretofore described,

extending transversely of the body of the machine. This pivotal connection is illustrated in Fig. 17, wherein it will be observed that one of the longitudinal spars of the planes, such as 35, has secured to it a metallic housing 36, which is provided with an elongated opening 37, in which elongated opening is a pin 38, which pin is mounted in the tubes 18. In this connection it will be noted that the tubes 18 form part of the triangular framework heretofore described, and project above and below the plane as illustrated in Figs. 1, 2, 4, 6, 8 and 9. By the pivotal connection above described and illustrated in Fig. 17, the supporting planes may be moved upwardly and downwardly without binding. During said operation, the pin 38 is free to shift its position by means of and in the elongated slot 37. From the foregoing it will be noted that each plane is pivoted at two points; that is to say, at its inner end to the rigid body portion of the machine, and intermediate of its ends to the triangular tubular framework disposed transversely of the rigid body portion of the machine. By causing the framework to move downwardly (assuming the body is held stationary or fixed), the planes are depressed. By causing the framework to move upwardly, the planes are elevated.

As heretofore stated, the triangular framework extending transversely of the machine, constructed as described, is movable relative to the body of the machine. If the machine is resting on the ground, the body may be moved up and down on the tubes 31 relative to this triangular framework. The movement of the body by assuming the framework to be stationary, that is, the machine being supported on the ground, will vary the angular relation of the supporting planes. The rigid body portion of the machine and the supporting planes are practically mounted in the triangular framework, between which and the triangular framework there is a relative movement. The mechanism for effecting this relative movement of the framework to the rigid body portion will be more fully hereinafter described.

Mounted on the lower end of the tube 18 is a resilient yielding skid 39, which is for the protection of the planes should the machine tend to alight inclined at an angle to the direction of the line of flight. In other words, each plane is provided for its protection with a yielding skid or shock absorber carried by the framework in which it is mounted.

Having described the rigid front body portion of the machine and the supporting planes and the triangular framework in which they are mounted, I will now describe the machine from the casing 1, or rigid body portion, rearwardly.

Secured in any suitable and mechanical manner to the rigid framework inclosed by the casing 1 and extending rearwardly therefrom, are flexible or adjustable members 40. These flexible or adjustable members 40 are approximately two-thirds of the length of the machine from the propeller shaft to the extreme rear end. They may be made out of any suitable material, 10 and, as heretofore stated, are secured in any suitable and mechanical manner to the framework of the rigid body portion of the machine inclosed by the casing 1. They are connected together throughout their 15 length at suitable distances apart by means of transverse members 41, 42, 43 and 44, and secured to each flexible member 40 at a point removed from the casing 1 are clips 45, to which are secured flexible members 20 46 and 47. These flexible members 46 and 47 are connected by the transverse members 41, 42 and 43. Secured also to the clips 45 are flexible members 48 and 49. Secured to the members 40 in the rear of the clips 45, 25 and to the flexible members 46, 47, 48 and 49, and to the transverse members 41, 42, 43 and 44, is a covering or fabric 50 of any suitable material.

The entire machine from the casing 1 30 rearwardly may be regarded as comprising a flexible body portion, it being that portion of the machine between the clips 45 and the casing 1 and the tail portion rearwardly of the clips 45, and the entire machine from the 35 casing 1 rearwardly may be gradually flexed, bent or adjusted upwardly or downwardly to lie on or describe arcs of circles of different radii; or it may be given a compound curvature, as illustrated in Fig. 1, 40 wherein is shown (in solid lines) the entire machine from the casing 1 rearwardly gradually curved upwardly, and the extreme terminal portion bent downwardly (as shown in dotted lines).

45 Located above and below the flexible members 40 and projecting rearwardly at an angle, are tubular U-shaped rigid members 51 and 52. The forward ends of these tubular U-shaped rigid members project 50 through the casing and are connected to the rigid framework of the machine in any suitable and mechanical manner and extend rearwardly, the member 51 being upwardly inclined and the member 52 being downwardly inclined, as illustrated in Fig. 1. 55 These members are connected together and braced by means of vertical tubes 53 and 54, and horizontal tubes 55 and 56, so as to form a rigid framework. These members 60 51 and 52, adjacent their ends and where they are bent, are provided with a series of small openings or perforations 57 for the passage of wiring.

Carried by the flexible members 40 to the 65 rear of the members 51 and 52, is an angu-

lar framework composed of vertical members 58 and 59, connected by members 60 and 61.

As heretofore stated, considering the machine from the front end of the propeller shaft to the extreme rear end, it is composed of a rigid body portion inclosed by the casing 1, a flexible body portion intermediate of the casing 1 and the clips 45, and a flexible tail in the rear of the clips 45.

Practically speaking, the longitudinal central axis of the machine from the propeller shaft to the extreme rear end may be adjusted to lie on or describe arcs of circles of different radii. When the machine from the casing 1 rearwardly is adjusted, bent, flexed or curved upwardly, as shown in full lines in Fig. 1, the supporting planes 10 are given their maximum elevation; or to state it in another way, when the supporting planes are given their maximum elevation by the relative movement of the triangular framework to the rigid body of the machine, the machine from the casing 1 rearwardly is curved upwardly. When said planes are 80 adjusted downwardly by the relative movement of the triangular framework to the body to their lowermost position, the rear flexible body and tail portion of the machine 85 is curved downwardly, as illustrated by 90 dotted lines in Fig. 1.

The major part of the longitudinal central axis of the machine may be curved, flexed or adjusted. This is important in maintaining and restoring the stability of the 100 machine. When the machine is traveling in what is regarded as straight flight, in which case the flexible body and tail portion is straightened out, then should the machine become unstable by adjusting it into its 105 curved form and elevating the wings or supporting planes, its stability may be restored. In other words, the machine may be adjusted, you might say, to a basin-like formation, which restores its stability.

I will now proceed to describe the mechanism by means of which the relative movement of the triangular framework to the rigid body portion of the machine is effected, and also the mechanism and wiring by 115 means of which the machine from the casing 1 rearwardly is bent, flexed, curved or adjusted. This mechanism is best illustrated in Figs. 1, 4, 5, 12, 13, 14, 15, 16, 18, 19 and 20. Mounted in the rigid body portion 120 on the inside of the casing 1 is a rotating shaft 62, on which is mounted the segment of a gear wheel 63. This segment of a gear wheel 63 engages with a rack 64, which rack is connected to and carried by spiders 65 and 66, which spiders are rigidly secured to the tubes 31 passing through the casing 1 and the rigid body portion. By moving this rack 64, which is connected by means 125 of the spiders 65 and 66 to the tubes 31, the 130

triangular framework extending transversely of the machine will be moved relative the rigid body portion of the machine, and consequently the supporting planes 5 which are pivoted to the machine, and intermediate of their ends to the triangular framework, will be moved. Connected to the shaft 62 at its opposite ends are sprocket wheels 67 and 68. The sprocket wheel 67 carries a sprocket chain 69, which sprocket chain 69 passes over a sprocket wheel 70 mounted on a stationary shaft 71. The sprocket wheel 68 carries a sprocket chain 72, which sprocket chain 72 passes over a 15 sprocket wheel 73 mounted indirectly on the stationary shaft 71. Connected to the hub of the sprocket wheel 70 and formed integral therewith, is a sprocket wheel 74, and keyed to the hub of the sprocket wheel 74 is 20 a lever 75. Keyed to the stationary shaft 71 is a double ratchet wheel 76, one portion of which has teeth extending in one direction and the other portion in the opposite direction. Adapted to engage in these teeth are 25 spring held pawls 77 and 78, which are controlled or released by the wire 79 passing to a small operating lever 80 pivoted to the operating lever 75. The operating lever 75 is U-shaped, one end being mounted on the 30 hub of the sprocket wheel 74, as above described, and the other end mounted on the hub 81 of a sprocket wheel 82. Also on the hub 81 of the sprocket wheel 82 the sprocket wheel 73 is directly mounted. The lever 75 alone rotates the sprocket wheels 70, 74, 82 35 and 73. Also mounted on the stationary shaft 71 are sprocket wheels 83 and 84, and these sprocket wheels 83 and 84 are operated by a U-shaped lever 85, the free ends 40 of which are keyed to the hubs of the sprocket wheels 83 and 84.

The U-shaped lever 85 and the lever 75 may be locked together and moved together, or the lever 85 may be disengaged from the 45 lever 75 and operated independently, and when operated independently, that is to say when it is not connected to the lever 75, it rotates only the sprocket wheels 83 and 84. Of course when the two levers 75 and 85 are 50 locked together and moved, they operate all the sprocket wheels mounted on the stationary shaft 71. The lever 85 is locked to the lever 75, as per the construction illustrated in Figs. 15, 16 and 18, wherein the lever 85 carries a spring held button 86, the stem of which button 86 passes through an opening of the lever 85, and when engaged its free end is seated in the opening 87 of the lever 75, it being held seated in said opening 55 by means of a spring 88 lying on the face of the lever 85 and the shoulder 89 on the stem of the button. The stem of the button 86 is released from the opening 87 by means of a lever 90 carrying on its lower end a wedge-shaped member 91. By pulling the lever 90

toward the handle of the lever 85, the wedge-shaped member 91 will release the end of the stem of the button 86 from the opening 87, thus disengaging the levers and permitting the lever 85 to be operated independently of the lever 75. By this connection the two levers 75 and 85 may be operated together, or the lever 85 may be operated independently of the lever 75. When the two levers 75 and 85 are locked together by the connection as above described, by operating the lever 75 the sprocket wheels 70, 74, 83, 84, 82 and 73 are rotated together. If said levers are disengaged by pressing on the lever 90, the lever 85, and consequently 70 the sprocket wheels 83 and 84, may be operated independently of the lever 75 and the sprocket wheels 70, 74, 82 and 73, above 75 enumerated, which it, the lever 75, operates. 80

In Fig. 18 I have shown diagrammatically the wiring for the rear flexible portion of the machine from the casing 1 rearwardly, and three banks of pulleys which control and operate said wiring, and the connection between said banks of pulleys and the sprocket 85 wheels 74, 83, 84 and 82. The banks of differential pulleys are mounted on a shaft 92 and comprise driven pulleys 93, 94 and 95 and a driving pulley 96 mounted on one end of said shaft 92, and on the opposite 90 end of said shaft 92 are driven pulleys 97, 98 and 99 and a driving pulley 100, and intermediate of these pulleys, from 93 to 100 inclusive, are driven pulleys 101, 102, 103 and 104 and driving pulleys 105 and 106. 95 It will be noted that the bank of pulleys from 93 to 96 inclusive are separate pulleys fastened or held together; likewise the bank of pulleys from 97 to 100 inclusive; and also the bank of pulleys from 101 to 106 inclusive; but, if desired, each bank may be formed integral and provided with separate grooves for the wiring. Mounted on the sprocket wheel 82 is a sprocket chain 107, and secured to this sprocket chain 107 is a 100 wire 108 which passes over the driving pulley 96. Mounted on the sprocket wheel 74 is a sprocket chain 109, and secured to the sprocket chain 109 is a wire or cable 110, which passes over the driving pulley 110. Mounted on the sprocket wheel 84 is a sprocket chain 111, which has secured to it a wire or cable 112, which passes over the driving pulley 106, and mounted on the sprocket wheel 83 is a sprocket chain 113, 115 which has secured to it a wire or cable 114, which passes over a driving pulley 105. 120

The sprocket wheels 83 and 84 may be operated independently by the lever 85 when disengaged from the lever 75, by means of 125 which operation the driving pulleys 105 and 106 may be operated, and which driving pulleys operate the driven pulleys 101, 102, 103 and 104. When the two levers 85 and 75 are locked together and moved, all the banks 130

of driving and driven pulleys mounted on the shaft 92 are rotated. Mounted on the driven pulleys 101 and 102 are wires 115 and 116, which wires pass around said pulleys and are secured to the pulleys by means of staples or any suitable device, as illustrated in Fig. 19, and one of the ends thereof is passed back through one branch of the tubular U-shaped member 51 and secured 5 to one of the flexible members 40 at the points *b* and *c*. The opposite ends of said wires 115 and 116 are fed back through one branch of the tubular member 52 and connected to the same flexible member 40 at the 10 same points, *b* and *c*. Located on the driven pulleys 103 and 104 are wires 117 and 118, one end of which passes back through one branch of the member 51 and are secured to one of the flexible members 40 at *d* and *e*, 15 and the opposite ends are passed back through one branch of the member 52 and secured to the same member 40 at the same points. Mounted on the driven pulleys 93, 94 and 95 are wires or cables 119, 120 and 20 121, which are likewise secured to said driven pulleys. One of their ends pass back through one branch of the member 51 and the opposite ends pass back through one branch of the member 52 and are secured 25 to one of the flexible members 40 at the points *f*, *g* and *h*. Mounted on the driven pulleys 97, 98 and 99 are wires 122, 123 and 124. One of their ends pass back through one branch of the member 51 and the opposite ends pass back through one branch of the member 52 and are secured 30 to one of the flexible members 40 at the points *i*, *j* and *k*. It will be observed that all the wires located 35 on the driven pulleys are secured intermediate of their ends to the respective pulleys, so that when the driven pulleys are rotated, one part of the wires becomes slack and the other taut.

By referring to Fig. 18, it will be observed 40 that if the levers 75 and 85 are locked together and pushed forwardly to the right, the triangular framework will be elevated and all the driving and driven pulleys mounted on the shaft 92 will be rotated 45 toward the right. By this operation, the entire rear flexible body and tail portion of the machine rearwardly of the casing 1 will be bent, flexed or adjusted upwardly. The reverse of this operation will bend, flex or 50 adjust the entire rear flexible body and tail portion downwardly. If it is desired to adjust the rear terminal portion of the tail independently of the remaining portion of the tail and flexible body portion, the lever 85 55 is unlocked from the lever 75, and the forward movement of the lever 85 disengaged from the lever 75 will bend, flex or adjust the rear terminal portion upwardly, and the reverse of this movement will bend, flex or 60 adjust the rear terminal portion down- 65

wardly. If it is desired to give the rear flexible body and tail portion a compound curvature, the entire portion of the machine from the casing 1 rearwardly is first adjusted, bent or flexed in an upward curvature, as illustrated in Fig. 1, and then by disengaging the lever 85 from the lever 75 and pulling it toward the left, as in Fig. 18, the rear terminal portion may be bent downwardly, as illustrated in Fig. 1.

It will be observed that the wiring, which bends, flexes or adjusts all that portion of the machine from the casing 1 rearwardly is attached to the flexible members 40 at different points throughout their lengths, so as to give said portion a gradual and uniform curvature.

The machine is held in the desired adjustment by means of the spring held pawls 77 and 78 engaging with the double ratchet 85 wheel 76 (see Fig. 14).

Located underneath each supporting plane near the terminal portions thereof are pivoted drags 125 and 126, which drags are opened and closed by means of wires 90 127 and 128, which are fed through the triangular framework and are connected to a lever or handle located on the inside of the casing 1 of the rigid body portion of the machine (not shown). The triangular 95 framework carries an axle 129, on which are mounted wheels 130, and mounted intermediate of these wheels is a yielding skid or shock absorber 131.

Secured to the rigid framework in the 100 rear of the machine is a wheel 132. When the machine is fully resting on the ground and straightened out, it is supported by the wheels 130 and 132. However, in Figs. 1 and 2, the machine is shown just ready to 105 ascend.

From the foregoing description, it will be seen that the supporting or sustaining planes 10 are pivoted to the rigid body portion of the machine and disposed at a dihedral angle, which angle may be varied by the relative movement of the triangular framework extending transversely of the machine to the body, and that this relative movement may be effected by the operation 110 of the lever 75. When the levers 75 and 85 are locked together, by pushing forwardly on the same the rear flexible body portion of the machine from the casing 1 rearwardly is bent, flexed or adjusted upwardly, and simultaneously with this upward movement the triangular framework is moved upwardly, carrying with it the supporting planes. The reverse of this operation will lower the triangular framework 115 and the supporting planes, and curve, bend or adjust downwardly the rear flexible body portion of the machine. When the rear flexible body portion has been curved upwardly, as illustrated in Fig. 1, and con- 120 125 130 135 140 145 150 155 160 165 170 175 180

sequently the supporting planes elevated, the rear tip of the machine may be curved downwardly, as illustrated in dotted lines in Fig. 1, by operating the lever 85 independently of the lever 75. In other words, the entire rear flexible body portion of the machine from the casing 1 rearwardly may be curved, bent or adjusted upwardly or downwardly, which is effected when the lever 85 is locked to the lever 75, or the extreme tip may be bent, curved or adjusted upwardly or downwardly by operating the lever 85 independently of the lever 75. Then again, the rear flexible body portion may be held straight and, as above stated, curved upwardly or downwardly, or the terminal portion may be operated independently of the rest of the flexible body portion by the independent operation of the lever 85, or it may be given a compound curvature, as above described.

It will also be noted that the supporting planes 10 may be flexed at their terminal portions, which obviates the necessity of flexing or adjusting the entire planes, and that the planes are concaved in their terminal portions, as at 12, and intermediate of the terminal portions and their points of attachment to the rigid body portion are also concaved, as at 12, and between the concaved portions of each plane at about the position where the tube 18 passes through the plane, the planes are slightly depressed. This concaved portion is for the purpose of offering an increased resistance should the machine dip at an angle to the line of flight. It will be further observed that each plane is mounted in the triangular framework extending transversely of the machine, which strengthens the plane. The capability of the major part of the longitudinal central axis of the machine to be bent, flexed, curved or adjusted, is advantageous in restoring the stability of the machine should it be displaced. It is also advantageous in gliding and descending, and it is further advantageous in maintaining the center of the sum of the weights (center of gravity) in a fixed relation to the center of the sum of the supports.

The flexible body portion of the machine is mounted in a rigid framework projecting rearwardly of the rigid body portion, the said rigid framework being spaced apart from the flexible body portion so that the flexible body portion may be given the proper upward and downward movement, and the flexible tail is mounted in a movable framework. The members 40, which constitute the essential part of the flexible body and tail portion, diverge and are formed of continuous flexible pieces of material.

The employment of the movable transversely disposed framework pivoted to the planes near their ends gives increased lever-

age for the adjustment of the planes and obviates the necessity of wiring for the supporting and adjustment of the planes. By this arrangement the planes can be adjusted by the expenditure of very little energy 70 on the part of the aviator.

The capability of the rear flexible terminal portions of the supporting planes to be bent, flexed or adjusted independently of each other and the adjustment of the planes is advantageous in steering and varying the effective supporting force and power of each plane. 75

The terminal portion of each plane is concaved in all of its adjustments and removed from the concaved terminal portion each plane is provided with another concaved portion. These two concaved portions, aside from the previous advantages mentioned, form air cushions beneath the planes, which tend to act as a propelling force. The pivoted drags located beneath each plane may be operated independently of each other, and are effective in steering and in maintaining and restoring the lateral 80 stability of the machine. 85

I claim:

1. A flying machine, comprising a rigid body portion, a flexible body and tail portion, movable supporting planes set on the rigid body portion at a dihedral angle, a member disposed transversely to the rigid body portion and movable relative thereto, and means for adjusting said member for changing the dihedral angle of the supporting planes. 95 100

2. A flying machine, comprising a rigid body portion, a flexible body portion and tail, a triangular framework disposed transversely of the rigid body portion and movable relative thereto, supporting planes set on the rigid body portion and mounted in said triangular framework, and means for causing relative movement of said triangular framework to said rigid body portion and simultaneously flexing the flexible body portion and tail. 105 110

3. In a flying machine, a supporting plane provided with a concave surface near its end and having its angle of ascendance prolonged to the extreme end in a semi-circle, whereby the same resistance is offered to the incoming air, should the machine dip at an angle to the line of flight, as to the front cutting edge of the plane. 115

4. In a flying machine, having a rigid body portion, a triangular framework disposed transversely of said rigid body portion and movable relative to said rigid body portion, supporting planes mounted in said triangular framework, and a resilient skid carried by the terminal portions of the triangular framework for the protection of the planes when the machine alights. 120 125

5. A flying machine, having a rigid body 130

portion, a flexible body portion and tail, a triangular framework disposed transversely of said rigid body portion and movable relative thereto, supporting planes pivoted to said rigid body portion and to said triangular framework, and means for the simultaneous operation of said framework and said flexible body and tail portion.

6. A flying machine, having a longitudinal central axis capable of being flexed, to lie on or describe arcs of circles of different radii, supporting planes mounted on axes running with the body of the machine and mounted at a dihedral angle, a triangular framework pivoted to said supporting planes, and means for the simultaneous operation of said triangular framework and the adjustment of the longitudinal central axis of the machine.

20. 7. A flying machine, comprising a rigid body portion and a flexible body portion and tail, a transversely disposed triangular framework, supporting planes pivoted to the rigid body portion and to said framework, means for moving said triangular framework relative to said body portion and tail portion, and a yielding skid carried by the supporting planes.

8. A flying machine, comprising a casing and a rigid body portion inclosed thereby, a transversely disposed triangular framework carried by said rigid body portion and movable relative thereto, supporting planes pivoted to said triangular framework and said rigid body portion, a rigid framework projecting rearwardly from said casing, a flexible body portion mounted therein, and means for the simultaneous operation of said flexible body portion and said triangular framework.

40. 9. In a flying machine, a supporting plane provided along its margin with a flexible member, a guide-way for the free end of said member, foot levers, and connections between the free end of said flexible member and said foot levers for adjusting said member upwardly and downwardly.

10. In a flying machine, a supporting plane provided with two distinct concave surfaces, one of such concave surfaces being rigid and near the body of the machine while the other of such concave surfaces is flexible and in the outer terminal portion of the plane.

55. 11. In a flying machine, including a rigid body portion, a transversely disposed framework within which said rigid body portion is mounted and on which it is movable, movable supporting planes operated by the frame, and a skid carried by said framework and mounted beneath the supporting planes.

65. 12. In a flying machine, a rigid body portion, a rigid framework projecting rearwardly from said rigid body portion, a flexi-

ble body and tail portion projecting rearwardly from said rigid body portion and within the rigid framework carried by said rigid body portion and spaced apart therefrom, and supporting planes carried by the rigid body portion, the said supporting planes being provided in their terminal portions with concaved flexible surfaces.

13. In a flying machine having a rigid body portion, a flexible body portion and tail, a framework disposed transversely of said rigid body portion and movable relative thereto, supporting planes pivoted adjacent their terminal portions to said framework and at their inner ends to said rigid body portion, and a lever for the simultaneous operation of said framework and said flexible body and tail portion.

14. A flying machine, comprising a framework, a rigid body portion mounted on said framework and vertically movable thereon, supporting planes provided with flexible concave surfaces pivoted to said body portion and also to said framework, an operating lever and connection between said lever and said framework whereby by the operation of said lever said framework is relatively adjusted vertically to the body and the supporting planes are adjusted vertically by the operation of the framework.

15. In a flying machine of the monoplane type, a rigid body portion, a flexible body and tail portion, a transversely disposed framework on which said rigid body portion is mounted, supporting planes mounted in said framework, a depending member carried by each end of said framework and projecting beneath the supporting planes, and a yielding skid or shock absorber carried by each depending member for the protection of the planes when the machine alights.

16. In a flying machine of the monoplane type, a rigid body portion, a flexible body and tail portion, a transversely disposed framework on which said rigid body portion is mounted, supporting planes mounted in said framework, a depending member carried by each end of said framework and projecting beneath the supporting planes, a yielding skid or shock absorber carried by each depending member for the protection of the planes when the machine alights, and a drag beneath each plane.

17. In a flying machine, having a rigid body portion and a flexible body portion and tail, a framework disposed transversely of said rigid body portion, a rigid framework disposed and projecting from the rear of said rigid body portion, a pair of supporting planes mounted in said transversely disposed framework, a skid carried by said transversely disposed framework and mounted beneath the planes, and a drag mounted beneath each plane, the flexible rear body portion being mounted in the rigid frame-

work projecting from the rear of said rigid body portion.

18. In a flying machine of the monoplane type, a supporting plane provided near its terminal portion with a concave surface and having its angle of ascendance prolonged to the extreme end and beyond the longitudinal axis of the plane in a semicircle, whereby the same resistance is offered to the incoming air 10 should the machine dip at an angle to the

line of flight as to the front cutting edge of the plane.

In testimony whereof, I have signed my name to this specification, in presence of two subscribing witnesses.

LEWIS GINTER YOUNG.
